J. KAUFMAN

VENTILATED CAP

Filed Aug. 29, 1923

FIG 1.

FIG 2.

FIG 3.

INVENTOR,
Jacob Kaufman
BY Frederick C. Bromley

ATTY -

UNITED STATES PATENT OFFICE.

JACOB KAUFMAN, OF TORONTO, ONTARIO, CANADA.

VENTILATED CAP.

Application filed August 29, 1923. Serial No. 660,016.

To all whom it may concern:

Be it known that I, JACOB KAUFMAN, a citizen of the United States of America, and resident of 10 Palmerston Avenue, in the 5 city of Toronto, Province of Ontario, Dominion of Canada, have invented certain new and useful Improvements in Ventilated Caps, of which the following is a specification.

- 10 The invention relates to certain new and useful improvements in caps as described in the present specification and shown in the accompanying drawing that forms part of the same.
- 15 The invention consists of the novel construction and arrangement of parts in a ventilated cap whereby an effective circulation of air can be obtained thus ventilating the interior thereof.
- 20 The object of the invention is to provide an all-season head-gear, one in which ventilation may be controlled at the pleasure of the wearer by means of a detachable strap disposed across the source of ventilation.
- 25 Further objects of the invention are to produce a cap the ventilation of which will not detract from the general exterior appearance, one which will be serviceable and comparatively inexpensive to manufacture.
- 30 In the drawing, Figure 1 is a perspective view of a cap embodying the invention, the front portion being raised from the visor to disclose perforations.

Figure 2 is a fragmentary sectional view 35 of the cap with the front portion in its normal position.

Figure 3 is a view of a modified form of perforations.

Like numerals of reference indicate corresponding parts in each figure of the drawing.

In the drawing, 1 designates the crown of the cap which may be either of conventional design or otherwise as desirable.

45 2 is the customary visor affixed to the crown and bearing a section 1 of a dome fastener as at 3, which section engages corresponding complementary sections carried by the overlapping front portion 4 of said crown.

50 5 is the sweat-band disposed about the front of the cap.

6 is a band partially encircling the orifice at the front of the cap and suitably reinforced to impart stiffness thereto, such band

extending upwardly from the visor and being separated from the sweat-band by a comparatively small air-space.

7 are a series of perforations arranged in said band 6 and communicating with the 60 cap interior, such perforations being staggered as shown in the drawing or otherwise relatively positioned as may be found desirable; such perforations consisting of small circular openings, buttonhole stitched or 65 having eyelets.

Figure 3 illustrates a slightly modified form of eyelet as at 8 which bears a screen 9 to prevent dust from entering the passage. 10 is a plate of non-flexible material 70 secured to the eyelets respectively in the cap interior, such being provided for the purpose of holding the eyelets in their place and preventing the band 6 from bending.

11 is a strap adapted to extend over the 75 band 6 for the purpose of covering the perforations and excluding the ingress of air when so desired; primarily in cold and inclement weather; each of the termini of said strap bearing buttonholes 12 for fastening on buttons 13 and 14 disposed at each side of the cap.

It will be manifest that other means may be conveniently employed to secure the strap termini, such as dome fasteners or hooks and 85 eyes and for this reason it is not intended to limit the invention in this regard to the specific form above recounted.

In the use of this cap, the overlapping portion 4 thereof is secured to the visor 2, 90 thus practically concealing the perforations from view without precluding ventilation of the cap interior. On such occasions that ventilation is not required, the strap 11 is fastened as hereinbefore described thus 95 covering the said perforations.

What I claim is:—

In a cap of the kind referred to, a pliant crown substantially reinforced above its visor, a series of perforations disposed in 100 such crown reinforcement, a strap partially encircling the crown for the purpose of covering said perforations, and means to detachably secure said strap to the crown.

Signed at Toronto, Ontario, Canada, this 105 25th day of August 1923.

JACOB KAUFMAN.
